INSTRUMENT FOR MEASURING DISSOLVED OXYGEN OR THE LIKE

Joseph Alan Huntsman, 3041 West Chester Pike,
Broomall, Pa.

Filed Apr. 17, 1964, Ser. No. 79,561

Term of patent 14 years

(Cl. D52—6)

Fig. 1.

Fig. 2.

FIG. 1 is a front perspective view, from above and to the left of center, of an instrument for measuring dissolved oxygen or the like showing my new design, and

FIG. 2 is a view of the same instrument in left side elevation.

The right side, not shown, is a mirror image of the illustrated left side. The bottom and rear surfaces, also not shown, are plain and flat. The dominant features of the design reside in the portions shown in solid lines.

I claim:

The ornamental design for an instrument for measuring dissolved oxygen or the like, as shown and described.
